UNITED STATES PATENT OFFICE.

GEORGE M. ANDERSON, OF INDIANAPOLIS, INDIANA, ASSIGNOR OF ONE-HALF TO RUBY STONE, OF SAME PLACE.

DESIGN FOR A ROCKING SEESAW.

SPECIFICATION forming part of Design No. 29,576, dated November 1, 1898.

Application filed October 7, 1898. Serial No. 692,954. Term of patent 14 years.

To all whom it may concern:

Be it known that I, GEORGE M. ANDERSON, a citizen of the United States, residing at Indianapolis, in the county of Marion and State 5 of Indiana, have invented and produced a new and original Design for Rocking Seesaws, of which the following is a specification.

Referring to the accompanying drawings, which are made a part hereof and on which 10 similar letters of reference indicate similar parts, Figure 1 is a perspective view of a rocking seesaw, showing my new design; Fig. 2, a central longitudinal vertical sectional view of the same, and Fig. 3 a transverse vertical 15 sectional view thereof.

As shown in said drawings, the rocking seesaw of my design has two frames in the form of a cross, each composed of the two members *a* and *b*, two rockers *c*, two corresponding 20 curved bars *d*, extending from end to end of the structure, three transverse seats *e*, *f*, and *g*, one at each end and one in the middle, and suitable transverse pieces *h*, forming a floor. The rockers and the curved bars connect at

the ends to the longer members *a* of the 25 frames and centrally to the ends of the shorter members *b* of said frames, while the seats *e*, *f*, and *g* rest upon the upper side of the longer frame members *a* and the floor-pieces *h* rest on the upper sides of the rockers *c*. These 30 parts, when assembled as shown, form a simple and pleasing design for that variety of child's plaything known as a "seesaw," and constitute a new, useful, and ornamental structure of the character.

Having thus fully described my said invention, what I claim as new, and desire to secure by Letters Patent, is—

The design for a rocking seesaw, substantially as herein shown and described. 40

In witness whereof I have hereunto set my hand and seal at Indianapolis, Indiana, this 5th day of October, A. D. 1898.

GEORGE M. ANDERSON. [L. S.]
